COMBINED SAW HORSE AND TOOL CHEST

Luigi Polselli, Philadelphia, Pa.

Application June 15, 1953, Serial No. 361,477

1 Claim. (Cl. 144—285)

This invention relates to a combined, portable saw horse and tool chest.

The object of the invention is to produce an improved device of the character stated.

In the accompany drawings:

Fig. 1 is a perspective view of a combined, portable, saw horse and tool chest embodying the invention, the same being shown in its erected, or operating position with the tool chest door in open position.

Fig. 2 is a sectional view taken on line 2—2 on Fig. 1.

Fig. 3 is a fragmentary, enlarged, sectional view taken on line 3—3 on Fig. 2.

Fig. 4 is an enlarged, fragmentary view, partly in section and partly in elevation, showing details of construction.

Fig. 5 is a sectional view on line 5—5 on Fig. 4.

Fig. 6 is similar to Fig. 5 showing the structure and the manner of operation of one of the legs of the device.

Fig. 7 is a reduced perspective view showing how the device is stored away or carried from place to another.

The device illustrated includes a combined saw horse and tool chest and folding legs for supporting the same.

The combined saw horse and tool chest is formed of a bottom wall 10, a top wall 12, end walls 14 and 15 and a rear wall 16. The front of the tool chest is open and is adapted to be closed by a door 18, hinged at 19 and held in closed position by any suitable lock or latch 20 part of which is carried by the door and part of which is carried by the front edge of the top wall 12. The top wall 12 serves to support a piece of wood to be cut and the walls 10, 12, 14, 15 and 16 are secured together to form an upper compartment to receive tools such as hammers, hatchets, etc., and a partition 22 is provided to form a lower compartment for receiving saws, measuring rules and the like.

In order to provide the necessary rigidity, the walls 10, 12, 14, 15 and 16 are secured, as at 24, to rigid end frames 28 which are made of a light rigid alloy and which include flanges 30 for supporting false bottom 22.

The combined saw horse and tool chest is supported by folding legs which are identical in structure and operation and only one of which will be described in detail.

Within the corners of the combined saw horse and tool chest are four hollow members 32 which are rigidly secured in position, as by being welded to the frame work 28, and the lower ends 36 of which project below the bottom wall 10 of the chest. Within each hollow member 32 is a tension spring 38 which is secured at its upper end to the upper end of the hollow member 32. It will be noted that when spring 38 is relaxed, it is shorter than corresponding hollow member 32. The tool chest, when in use, is supported on four legs 34 which are foldable against the underside of the chest when the same is not in use. Since the structure and operation of all four

2

legs are identical, only one of them will be described in detail. Each leg 34 includes an upper reduced portion 42 which is turned down to form conical portion 44 which terminates in a pin 46 which is suitably attached to the lower end of spring 38. Pin 46 is small enough readily to enter notch 48 in the edge of the lower end 36 of corresponding fixed hollow member 32. The bottom wall 10 of the chest is provided with clips 50 for receiving and retaining the legs 34 when the latter are in the folded position shown in Fig. 6. The operation is as follows:

To erect the legs into the supporting position of Fig. 2, they are disengaged from clips 50 whereupon they move by gravity to a substantial vertical position in which pins 46 are disengaged from notches 48. Springs 38 now draw the legs upwardly until the reduced portions 42 of the legs seat within the lower portions 36 of fixed members 32 as shown in Fig. 5. To fold the legs against the underside of the chest as shown in Fig. 6, the legs 34 are pulled down until the conical portions 44 thereof clear the edges of the lower ends 36 of the fixed members 32, whereupon, the legs are rotated from the vertical to the horizontal position until pins 46 engage notches 48 and legs engage clips 50 which retain the legs in the horizontal position of Fig. 6.

From the foregoing it will be seen that by merely raising the chest to the necessary extent and detaching the legs 34 from the spring clips 50, the springs 38 automatically draw the legs to the vertical supporting position of Fig. 5.

In order to carry the device around, I provide a handle 52 which is adapted to seat in a recess 54 formed in top wall 12 so as to be out of the way when the top wall 12 is supporting a board to be cut.

What I claim is:

A combined portable saw horse and tool chest including a top wall, a bottom wall, end walls and side walls which coact to define a tool receiving receptacle, the upper side of said top wall being flat to support a board to be sawed, there being an access opening formed in one of said side walls, a door for closing said opening, hollow members fixedly carried by, and extending below the bottom of, said receptacle, a tension spring disposed within each of said hollow members and having its upper end connected to the upper end of the hollow member, said spring being shorter than the corresponding hollow member, a leg associated with each of said hollow members for supporting said tool chest, each leg including an upper reduced portion adapted to seat within the lower end of the corresponding hollow member, a pin extending upwardly from said reduced portion and connected to the lower end of said spring, there being a notch in the lower edge of each hollow member adapted to be engaged by said pin when the corresponding leg is moved to a horizontal position against the underside of said chest, and spring clips carried by the underside of said chest for receiving said legs and retaining them in said horizontal position.
